No. 36,887.

Patented April 26, 1904.

UNITED STATES PATENT OFFICE.

NATHANIEAL M. KIRSHNER, OF BUFFALO, NEW YORK.

DESIGN FOR A BADGE.

SPECIFICATION forming part of Design No. 36,887, dated April 26, 1904.

Application filed March 21, 1904. Serial No. 199,295. Term of patent 3½ years.

To all whom it may concern:

Be it known that I, NATHANIEAL M. KIRSHNER, a citizen of the United States, and a resident of Buffalo, in the county of Erie and State 5 of New York, have invented a new, original, and ornamental Design for a Badge, of which the following is a specification, reference being had to the accompanying drawing, forming a part thereof.

The figure of the drawing shows a plan view ¹⁰ of the badge-body of my design.

I claim—

The ornamental design for a badge, as shown.

NATHANIEAL M. KIRSHNER.
